ELECTRIC PROTECTION FOR LOOMS

Charles W. Moss, Canton, Mass., assignor to
Crompton & Knowles Loom Works, Worcester,
Mass., a corporation of Massachusetts

Application March 10, 1950, Serial No. 148,911

20 Claims. (Cl. 139—341)

1

This is a continuation in part of my co-pending application Serial No. 134,001, filed December 20, 1949, now abandoned.

This invention relates to improvements in electric protection for looms of the type wherein a shuttle changes the electric condition of a switch while it is in flight across the lay, and it is the general object of the invention to provide control means for the switch enabling the latter to be held closed or open for a period of time greater than that required for the shuttle to pass it.

In co-pending application Serial No. 121,002 filed by Moss and Blanchard there is set forth an electric protection having an electric circuit containing a loom controlling relay normally energized but effective when deenergized to effect prompt loom stoppage. One of the circuits for the relay has two parallel branches one of which contains a timer switch and the other of which contains the aforesaid shuttle operated switch. Another of the circuits shown in that application shows a single circuit with the timer switch in series with the shuttle operated switch. In both circuits the timer switch is set to open at a given time in the loom cycle when the shuttle, if on time, reaches a given point along the lay. The shuttle switch is closed or open, depending upon the type of circuit used by the shuttle during a period corresponding approximately to the interval of opening or closing of the timer switch, so that if the shuttle is running correctly and parallel circuits are used one or the other of the branch circuits will always be closed and the relay will remain energized to permit loom operation. If, on the other hand, the shuttle should be running slow and not close its branch circuit until after the timer switch branch circuit is open the relay becomes deenergized with resultant loom stoppage. When a series circuit is used one or the other of the switches will always be open if the shuttle is running correctly, but if the shuttle is late its switch will be closed when the timer switch is closed and this condition will result in loom stoppage.

In practice it is found that a shuttle will not always run in exactly the same time every pick of the loom. Occasionally the shuttle will be ahead of time and the period of closure or opening of the shuttle switch will end while the timer switch is still open or closed. Under these conditions the loom will be stopped although the shuttle will have reached its shuttle box in ample time and there is no necessity for protecting the loom. Also, the timer switch will not always

2

close or open promptly depending upon the type of circuit used when the shuttle switch opens or closes after its period of operation and closure, with resultant loom stoppage even though the shuttle is running on time.

In order to meet the foregoing conditions relative to early flight of the shuttle and the occasional slowness of operation of the timer switch it is an important object of the present invention to provide means which will hold the shuttle switch in the position to which the shuttle moves it from the time the shuttle operates it until some later time after the timer switch has had ample opportunity to return to normal.

15 In order that the shuttle operated switch may be in condition for operation by the shuttle incident to each pick of the loom it is a further object of the invention to insure unlocking of the shuttle switch at some time in the loom 20 cycle between operation of the time switch and the following normal time for the shuttle to operate the shuttle switch. This result can be accomplished as set forth hereinafter by means of a cam which has periodic operative relation 25 with the lock to move the latter to releasing position. As shown herein this release occurs when the lay is near its front center position, but the invention is not necessarily limited to a release operation occurring at this time.

With these and other objects in view which will appear as the description proceeds, the invention resides in the combination and arrangement of parts hereinafter described and set forth.

In the accompanying drawings, wherein two 35 embodiments of the invention are set forth,

Fig. 1 is a front elevation of a loom having the preferred form of the invention applied thereto.

Fig. 2 is an enlarged front elevation of part of the mechanism shown in Fig. 1 setting forth the shuttle operated switch in its normal open position.

Fig. 3 is a view similar to Fig. 2 but showing the shuttle operated switch closed.

Fig. 4 is a fragmentary plan view looking in the direction of arrow 4, Fig. 2, showing the relation between the resetting cam and part of the switch locking mechanism.

Fig. 5 is a diagram of the electric circuit used 50 with the invention.

Fig. 6 is a timing diagram showing the relation of the opening interval for the timer switch and the closing period for the shuttle switch with respect to the various positions of the lay 55 for one pick of the loom.

Fig. 7 is an enlarged view looking in the direction of arrow 7, Fig. 1, showing the timer switch and the top shaft of the loom, the latter being in cross section.

Fig. 8 is a sectional plan view looking in the direction of line 8—8, Fig. 3.

Fig. 9 is a diagrammatic view showing the second or modified form of the invention wherein the timer and shuttle switches are in series, and

Fig. 10 is a time diagram similar to Fig. 6 corresponding to the modified form of the invention.

Referring particularly to Fig. 1, the loom frame 10 supports a lay 11 having a race plate 12 secured to the upper side thereof. Right and left gangs of shifting shuttle boxes RG and LG, respectively, are mounted on the lay for placing one or another of a plurality of shuttles S1, S2 and S3 in picking position. The gangs of shuttle boxes shift vertically with respect to the lay, box lifter rods 13 being provided for this purpose. The loom has right and left picker sticks 14 and 15, respectively, which operate when the lay is approximately on top center position to pick the shuttle in active position across the lay and along the race plate 12. As shown in Fig. 1 the shuttle S1 is in position to be picked from gang LG to gang RG.

The loom is provided with a driving motor M having a pinion 15 meshing with a gear 16 secured to the top shaft 17 of the loom. The top shaft has secured thereto near the ends thereof gears 18 meshing with gears 19 on the bottom shaft 20 of the loom. The picking mechanism not specifically shown herein will ordinarily be operated by the bottom shaft 20.

In the operation of the matter thus far described the lay swings backwardly and forwardly in usual manner and the actively placed shuttle is picked when the lay is moving rearwardly and is approximately on top center. The shuttle is in flight across the lay as the latter moves rearwardly and will ordinarily remain in flight until the lay reaches approximately its bottom center position, at which time the shuttle will enter the shuttle box which it is approaching. As the loom continues to run the pick of filling laid by the shuttle will be beaten into the fabric by the reed 21 as the lay reaches front center and when the lay again reaches top center position the picking cycle will be repeated.

If for any reason the shuttle should fail to clear the warp shed by the time the lay reaches a given position in the forward motion it is necessary to stop the loom in order to prevent warp breakage as the reed beats forward. In the previously mentioned copending application Serial No. 121,002 provision is made for determining the shuttle position while it is in flight along the lay between the shuttle box gangs RG and LG so that more time may be allowed for stopping the loom in the event that the shuttle position detecting means indicates that the shuttle is running slow and is likely not to clear the shed.

In the preferred form of the invention the lay is provided with a vertical bore 25 in which is mounted a shuttle operator or closer pin or plunger 26 having a head 27 on the lower end thereof. A bracket 28 is secured as at 29 to the under side of the lay and has mounted thereon for vertical adjustment a shuttle operated switch designated generally at SS. By means of a screw threaded stem 30 and nuts 31 and 32 located respectively above and below the

bracket 28 the vertical position of the switch SS can be adjusted.

The shuttle switch has a contact blade 35, see Fig. 3, normally spaced from a contact 36 carried by the switch SS. The blade is normally in open position but when the plunger 26 is depressed blade 35 engages contact 36 to close the switch. This closure may be effected by a second plunger 37 forming part of the switch SS and preferably aligned with the plunger 26. The loom is also provided with a preferably stationary timer switch TS which is normally closed and is provided with a roll 40 located in the path of a switch opener 41 secured to the top shaft 17, see Fig. 7.

As contemplated herein the loom is provided with control means which will act on the motor to stop the loom very promptly in the event the shuttle is running behind schedule. This result is accomplished by mechanism C indicated diagrammatically in Fig. 5 for the loom motor M. The controller C is dependent upon a relay R in such manner that so long as the relay is energized the controller C will permit continued operation of the loom, but when the relay becomes deenergized controller C immediately causes loom stoppage.

The electric circuit used with the invention, set forth in Fig. 5, includes a source of electric power, such as a transformer T, connected at one side by wire 45 to one side of the relay R, the other side of which is connected to a wire 46. The other side of the transformer is connected to a wire 47, and between the wires 46 and 47 there are two parallel branch circuits one of which, designated at TC, is the timer circuit and the other of which, shown at SC, is the shuttle switch circuit.

As set forth herein the timer circuit will be closed throughout the greater part of the loom cycle but will be open during a brief interval during which the shuttle if running on time will depress plunger 26 to effect closure of switch SS. Under these conditions one of the parallel branch circuits is open due to loom operation while the other is closed due to shuttle operation and so long as one or the other of these branch circuits is closed the relay will remain energized. If, however, the shuttle should be running slow and fail to depress plunger 26 until after the timer switch TS has been opened the relay R will become deenergized and the loom will be stopped.

That part of the foregoing description relating more particularly to the timer and shuttle switches may be similar to the matter shown in the aforesaid copending application. As already stated, if the shuttle should be running ahead of schedule it will close the switch SS ahead of the normal time for its closure in the loom cycle and permit opening of the shuttle switch while the timer switch is still open, a condition which would result in unnecessary loom stoppage. The present invention aims to provide means by which the shuttle switch can be held closed for a period of time longer than that required for the shuttle to pass over the plunger 26 so that even though the shuttle be early in its flight the loom can continue to run.

In carrying the invention into effect there is provided a latch member 50 pivoted as at 51 to the bracket 28. This member 50 extends between plungers 26 and 37 and has preferably a bent end 52 for cooperation with a lock or detent member 53 shown herein as a hook piv-

oted as at 54 to the bracket 28 and having a hook-head 55 capable of passing over the latch member 50. A light tension spring 56 interposed between the hook member and bracket 28 tends normally to move the hook head 55 to the right as viewed in Figs. 2 and 3, or to the position shown in full lines in Fig. 3.

The lower end of the lock member has rotatable thereon a roll 60 for cooperation with a cam 61 which is secured as at 62 to an intermediate stationary brace 63 of the loom. It is this brace which supports the timer switch TS as indicated in Fig. 1. Cam 61 has a low area 65, a rising or inclined area 66 and a high area 67. The cam is located under the lay with the high area 67 forward of the low area 65.

Fig. 6 indicates diagrammatically the timing of a one-pick cycle of the loom. In this figure it is assumed that the one-pick cycle starts at the left with the lay on front center, indicated at FC, and that the lay then passes through top center, TC, back center, BkC, bottom center, BtC, and back to front center. It is assumed that the plunger 26 is located at a point along the lay which the shuttle will reach when the lay is at back center, the interval of opening of the timer switch starting slightly before back center and terminating slightly thereafter.

In Fig. 6 the line *a* represents the closed condition of the timer switch, and the small gap *b* represents the interval of opening. Line *c* represents the time of closure of the shuttle switch if the shuttle is running on time, while the dotted line *d* represents the time of closure of the shuttle switch if the shuttle is running ahead of schedule.

In operation, the shuttle switch and parts associated therewith will normally be in the position shown in Fig. 2, the shuttle switch being open and the plunger 26 being in high position and extending into the path of the shuttle. Also, the head 55 of the lock member or detent will be against the end 52 of the latch 50. As the shuttle travels across the lay incident to picking it will depress plunger 26 and thereby lower the latch to a position which will permit the holding head 55 to move from the position shown in Fig. 2 to the full line position shown in Fig. 3. So long as the shuttle is passing over the plunger 26 the switch SS will be closed due to shuttle presence, but after the shuttle leaves the plunger 26 the latch will be held down in locked position to maintain the shuttle switch SS closed. As the lay continues to move forward roll 60 will engage the incline 66 of cam 61 and will rock the detent from the full line to the dot and dash line position shown in Fig. 3, thereby moving the locking head 55 away from the detent and permitting the latter to rise due to inherent resilience of the switch plate 35. The shuttle switch is then open in readiness for the next flight of the shuttle.

From Fig. 6 it will be understood that the period of opening represented at *b* occurs at a regularly recurring interval in the loom cycle at a time when the shuttle if running properly will reach a given point along the lay, that is, the point at which the plunger 26 is located. If the shuttle is running on time it will close the switch SS slightly before, or at least not later than the opening of the timer switch, and the locking mechanism will hold the switch SS closed until the lay by its advance movement causes the cam 61 to rock the detent to release

the shuttle switch. The shuttle switch is released after the timer switch has had ample time to close. If the shuttle should be running ahead of its schedule, as indicated by dotted line *d* in Fig. 6, it will depress plunger 26 earlier than usual, but the detent will nevertheless keep switch SS closed throughout the interval of opening of the timer switch.

In the modified form of the invention shown in Fig. 9 the timer switch 70 is normally open and will be closed by cam 71 momentarily at the time a normally closed shuttle detector switch 72 is opened by the plunger 26. These two switches 70 and 72 are in series with the relay 73 which, unlike relay R, is normally de-energized so that the switch 74 which it controls will normally be down against its contact 75 to maintain the previously described circuit through the loom controlling mechanism C.

In this modified form of the invention the circuit containing the relay R will always be open if the shuttle is running on time, due to the fact that the switch 70 will not close until slightly after switch 72 is opened due to downward movement of the plunger 26 by the shuttle, provided the latter is running on time. If, however, the shuttle should be late switch 72 will be closed at the same time that switch 70 closes and the circuit through the relay 73 will be completed and the latter will open the switch 74, thereby enabling the control C to effect prompt stoppage of the loom.

The diagram shown in Fig. 10 is very similar to that shown in Fig. 6 except that switch 70 represented by line 76 will not be closed until a short interval after the normal time for the opening of switch 72, lines 77 representing this time for normal opening of switch 72. The reason for this time relation, which is the reverse of that employed in the preferred form of the invention, is to prevent closure of the circuit through relay 73 when the shuttle is running properly. This timing feature is not essential, since the period of closure of switch 70 could be set to occur a very brief interval after the time of normal opening of switch 72 without allowing time for full energization of relay 73, but such a timing would involve the breaking of the circuit with resultant sparking at one or the other of the switches.

In the foregoing description specific forms of switches have been shown for both the timer and shuttle controlled branches of the electric circuit, but the invention is not limited to these specific switches. Also, the lay has been shown as having shuttle boxes at both ends thereof, but the invention is not limited to a loom of this type.

It will thus be seen that the preferred form of the invention sets forth simple means by which the shuttle operated switch, once closed by the shuttle, will remain closed until a later point in the loom cycle, at which time the holding mechanism for the shuttle switch is released. In this way the shuttle switch, if closed by a shuttle running ahead of schedule, will remain closed during the interval of opening of the timer switch. It will also be seen that the unlocking mechanism is moved to releasing position at some point in the loom cycle considerably after the shuttle passes over the plunger 26, and there is therefore no necessity for employing a timer switch which will close at a precise time in the loom cycle. The period of closure of a shuttle switch may if desired extend until the lay has almost reached its front center position, if lock re-

leasing means of the type employing a cam 61 is utilized. In the modified form of the invention the locking mechanism acts to hold the shuttle operated switch open and approximately the same length of time that it holds a shuttle operated switch of the preferred form closed. The lock can therefore be used with both forms of the invention.

Having thus described the invention it will be seen that changes and modifications of the foregoing specific disclosure may be made without departing from the spirit and scope of the invention.

What is claimed as new is:

1. In protection means for a loom having a shuttle which when running properly passes a given point along the lay at a given time in the loom cycle, a movable electric switch operator located at said given point normally extending into the path of the shuttle and moved by the latter when the shuttle passes said given point, an electric switch capable of being in either open or closed condition thereof and normally in one of said conditions and moved to the other condition when the operator is moved by the shuttle, lock means effective to hold the switch in said other condition, means releasing the lock means to enable the switch to return to said one condition thereof prior to the next arrival of the shuttle at said given point along the lay, electric circuit means including an electromagnetic device and said switch, and loom stopping means controlled by said electromagnetic device effective to stop the loom upon failure of the shuttle to move said operator and cause said switch to be in said other condition thereof at said given time in the cycle of the loom.

2. In protection means for a loom having a shuttle which when in flight traverses a path along the lay and when running properly passes a given point along the lay at a given time in the loom cycle, a movable electric switch operator under said path of the shuttle located at said given point normally extending upwardly into said path and depressed by the shuttle when the latter passes over the operator, an electric switch capable of being in either open or closed condition and normally in one of said conditions and being moved to the other condition thereof when the operator is depressed by the shuttle, lock means effective to hold the switch in said other condition, means releasing the lock means to enable the switch to return to said one condition thereof on the next beat-up of the lay, electric circuit means including an electromagnetic device and said electric switch, and loom stopping means controlled by said electromagnetic device effective to stop the loom upon failure of the shuttle to depress said operator and cause said electric switch to be in said other condition thereof at said given time in the loom cycle.

3. In protection means for a loom having a shuttle which when running properly passes a given point along the lay at a given time in the loom cycle, a movable electric switch operator located at said given point normally extending into the path of the shuttle and moved by the latter when the shuttle passes said given point, an electric switch capable of being in either open or closed condition thereof and normally in one of said conditions and moved to the other condition when the operator is moved by the shuttle, lock means on the lay effective to hold the switch in said other condition, means dependent upon motion of the lay releasing the lock means to en-

able the switch to return to said one condition thereof prior to the next arrival of the shuttle at said given point along the lay, electric circuit means including an electromagnetic device and said switch, and loom stopping means controlled by said electromagnetic device effective to stop the loom upon failure of the shuttle to move said operator and cause said switch to be in said other condition thereof at said given time in the cycle of the loom.

4. In electric protection means for a loom having a shuttle and lay, normally open electric switch means closed by the shuttle at a given time in the loom cycle if the shuttle is running on time, a timer electric switch normally closed but opening for an interval beginning substantially at said time in the cycle and closing at the end of said interval, means acting independently of the shuttle holding the switch means closed from the time of closure thereof by the shuttle until a point in the loom cycle subsequent to said interval, and electrically controlled means effective to stop the loom if the switch means is open during said interval.

5. In electric protection means for a loom having a shuttle and lay, normally open electric switch means closed by the shuttle at a given time in the loom cycle if the shuttle is running on time, a timer electric switch normally closed but opening for an interval beginning substantially at said time in the cycle and closing at the end of said interval, lock means holding the switch means closed from the time of closure thereof by the shuttle until a point in the loom cycle subsequent to said interval, and electrically controlled means effective to stop the loom if the switch means is open during said interval.

6. In electric protection means for a loom having a shuttle and lay, normally open electric switch means closed by the shuttle at a given time in each one pick cycle of the loom if the shuttle is running on time, a timer electric switch normally closed but opening for an interval beginning substantially at said time in each cycle and closing at the end of the interval, holding means independent of the shuttle maintaining the switch means closed after closure thereof by the shuttle, means cooperating with said holding means causing the latter to release the switch means at a time subsequent to said interval and prior to said given time in the next one pick cycle of the loom, and electrically controlled means effective to stop the loom if the switch means is open during said interval.

7. In electric protection means for a loom having a shuttle and lay, normally open electric switch means closed by the shuttle at a given time in each one pick cycle of the loom if the shuttle is running on time, a timer electric switch normally closed but opening for an interval beginning substantially at said given time in each cycle and closing at the end of the interval, holding means independent of the shuttle maintaining the switch means closed after closure thereof by the shuttle, means cooperating with said holding means causing the latter to release the switch means at a point in the loom cycle subsequent to said interval but within the one pick cycle in which the switch means is closed, and electrically controlled means effective to stop the loom if the switch means is open during said interval.

8. In electric protection means for a loom having a shuttle and lay, normally open electric switch means closed by the shuttle at a given time in each one pick cycle of the loom if

the shuttle is running on time, a timer electric switch normally closed but opening for an interval beginning substantially at said time in each cycle and closing at the end of the interval, holding means on the lay independent of the shuttle maintaining the switch means closed after closure thereof by the shuttle, means dependent upon motion of the lay cooperating with said holding means causing the latter to release the switch means at a time subsequent to said interval and prior to said given time in the next one pick cycle of the loom, and electrically controlled means effective to stop the loom if the switch means is open during said interval.

9. In electric protection means for a loom having a shuttle which when running properly passes a given point along the lay at a given time in the loom cycle, the loom having control means including an electric relay effective when the relay is energized to permit continued loom operation but effective when the relay is deenergized to cause loom stoppage, electric circuit means including the relay and two parallel branch circuits, an electric timer switch in one of said branch circuits opening for an interval at said time in the loom cycle and closing at the end of the interval, normally open electric shuttle switch means in the other branch circuit closed by the shuttle when the latter reaches said point along the lay, and control means for the shuttle switch means including a lock effective whenever the shuttle switch means is closed to maintain the latter closed and including a releaser for the lock effective subsequent to said interval to effect opening of said shuttle switch means.

10. In electric protection means for a loom having a lay and a shuttle, normally open electric switch means closed by the shuttle at a given time in each one pick cycle of the loom if the shuttle is running properly, loom controlling means including an electric relay effective when the relay is energized to permit continued loom operation but effective when the relay is deenergized to stop the loom, electric circuit means including the relay and two parallel branch circuits, a normally closed timer electric switch in one of said branch circuits opening at said time in each one-pick cycle of the loom for a brief interval and closing at the end of said interval, said switch means being in the other branch circuit, lock means effective upon closure of the switch means by the shuttle to maintain the switch means closed, and means operative due to motion of the lay causing the lock to unlock the switch means at a point in the loom cycle subsequent to said interval.

11. In electric protection means for a loom having a shuttle which when running properly passes a given point along the lay at a given time in the loom cycle, the loom having controlling means including an electric relay effective when the relay is energized to permit continued loom operation but effective when the relay is deenergized to stop the loom, electric circuit means including said relay and two parallel branch electric circuits, a loom controlled timer switch in one of said branch circuits normally closed but open due to loom operation for a brief interval at said given time in the loom cycle, a normally open shuttle operated switch tending normally to be in open position, means operated by the shuttle when the latter reaches said point along the lay effective to close the shuttle operated switch, means holding the shuttle operated switch in closed position after the shuttle has passed said point along the lay, and mechanism moving the

holding means to non-holding position relative to the shuttle operated switch subsequent to said interval, whereupon the shuttle operated switch moves to open position.

5 19. In electric protection means for a loom having a shuttle and a lay, normally open electric switch means closed by the shuttle at a given time in the loom cycle if the shuttle is running on time, loom controlling means including an electric relay effective when the relay is energized to permit continued loom operation but effective when the relay is deenergized to stop the loom, electric circuit means including the relay and two branch electric circuits, a timer switch in one branch circuit opening for a brief interval during the loom cycle at said given time, the normally open switch means being in the other branch circuit, means on the lay operated by the shuttle effective to close the switch means in said other branch circuit, the shuttle if running on time closing the switch means in said other branch circuit for the time the timer switch is open, the shuttle if running ahead of time closing said switch means earlier in the loom cycle than said given time and the switch means tending to open before the end of said interval, and control means for said normally open switch means effective upon closure of the latter by the shuttle when the latter is running ahead of time to maintain the switch means closed for a period ending after said interval.

20 25 30 35 40 45 50 55 60 65 70 75 13. In electric protection means for a loom having a shuttle and a lay, a support on the lay, normally open switch means on the support, a switch means operator on the lay moved by the shuttle to close the switch means at a given time in the loom cycle if the shuttle is running on time, loom controlling means including an electric relay effective when the relay is energized to permit continued loom operation but effective when the relay is deenergized to stop the loom, electric circuit means including said relay and two parallel branch circuits, a timer switch in one of said branch circuits normally closed but opening for a brief interval at said given time in the loom cycle, the normally open switch means being in the other branch circuit and tending normally to be in open position, a holding member on the support interposed between said switch means operator and the normally open switch means, a lock on the support effective when the operator is moved by the shuttle to engage the holding member and cause the latter to maintain the switch means on the support closed, a stationary cam on the loom, and means carried by the lay and operative due to motion of the lay subsequent to said interval to cooperate with said cam and move said lock to unlocking position relatively to said holding member, whereupon said normally open switch means moves to open position.

14. In electric protection means for a loom having a shuttle and lay, normally closed electric switch means opened by the shuttle at a given time in the loom cycle if the shuttle is running on time, a timer electric switch normally open but closing for an interval beginning substantially at said time in the cycle and opening at the end of said interval, means acting independently of the shuttle holding the switch means open from the time of opening thereof by the shuttle until a point in the loom cycle subsequent to said interval, and electrically controlled means effective to stop the loom if the switch means is closed during said interval.

11

15. In electric protection means for a loom having a shuttle and lay, normally closed electric switch means opened by the shuttle at a given time in the loom cycle if the shuttle is running on time, a timer electric switch normally open but closing for an interval beginning substantially at said time in the cycle and opening at the end of said interval, lock means holding the switch means open from the time of opening thereof by the shuttle until a point in the loom cycle subsequent to said interval, and electrically controlled means effective to stop the loom if the switch means is closed during said interval.

16. In electric protection means for a loom having a shuttle and lay, normally closed electric switch means opened by the shuttle at a given time in each one pick cycle of the loom if the shuttle is running on time, a timer electric switch normally open but closing for an interval beginning substantially at said time in each cycle and opening at the end of the interval, holding means independent of the shuttle maintaining the switch means open after opening thereof by the shuttle, means cooperating with said holding means causing the latter to release the switch means at a time subsequent to said interval and prior to said given time in the next one pick cycle of the loom, and electrically controlled means effective to stop the loom if the switch means is closed during said interval.

17. In electric protection means for a loom having a shuttle and lay, normally closed electric switch means opened by the shuttle at a given time in each one pick cycle of the loom if the shuttle is running on time, a timer electric switch normally open but closing for an interval beginning substantially at said given time in each cycle and opening at the end of the interval, holding means independent of the shuttle maintaining the switch means open after opening thereof by the shuttle, means cooperating with said holding means causing the latter to release the switch means at a point in the loom cycle subsequent to said interval but within the one pick cycle in which the switch means is opened, and electrically controlled means effective to stop the loom if the switch means is closed during said interval.

18. In electric protection means for a loom having a shuttle which when running properly passes a given point along the lay at a given time in the loom cycle, the loom having control means including an electric relay effective when deenergized to permit continued loom operation but effective when energized to cause the control means to effect loom stoppage, electric circuit means including the relay, an electric timer switch and a shuttle switch in series, the timer switch being normally open and closing for an interval at said time in the loom cycle and opening at the end of the interval, said shuttle switch being normally closed and being opened by the shuttle when the latter reaches said point along the lay, and control means for the shuttle switch

12

including a lock effective whenever the shuttle switch is opened by the shuttle to maintain said shuttle switch open, said control means including a releaser for the lock effective subsequent to said interval to cause the lock to release the shuttle switch, whereupon the latter returns to the normal closed condition thereof.

19. In electric protection means for a loom having a shuttle and a lay, normally open electric switch means closed by the shuttle at a given time in each one pick cycle of the loom when the shuttle is running on time, loom controlling means including an electric relay effective when the relay is energized to permit continued loom operation but effective when the relay is de-energized to stop the loom, a second electric switch means normally closed, electric circuit means including the relay and both of said switch means and dependent for closure thereof to maintain the relay energized upon closure of one or the other of said switch means, said second switch means opening for a brief interval at said given time in each loom cycle, the first named switch means if closed by the shuttle when the latter is running ahead of time tending to open after the shuttle passes said first switch means and while said second switch means is open during said interval, lock means effective when said first switch means is closed, whether the shuttle

20 be running on time or ahead of time, to maintain the first switch means closed, and releasing means moving the locking means to non-locking position with respect to the first switch means at a time in the loom cycle subsequent to said interval and prior to the said given time in the next one pick cycle of the loom.

20. In electric protection means for a loom having a shuttle and a lay, normally open electric circuit means closed at a given time in the loom cycle if the shuttle is running on time, a second electric circuit means normally closed but opening for an interval beginning substantially at said time in the cycle and closing at the end of said interval, means acting independently of the shuttle holding the first circuit means closed from the time of closure thereof until a point in the loom cycle subsequent to said interval, and electric means controlled by said first and second circuit means effective to stop the loom if the first circuit means is open during said interval.

CHARLES W. MOSS.
